J. W. Gibbs, of Albany, N. Y.
Assignor to
Abbott & Lawrence, of Philadelphia Pa.
Letters Patent No. 1107, Dated June 14, 1859.

The schedule referred to in these Letters Patent and making part of the same.

To all whom it may concern:

Be it known that J. W. Gibbs in the City of Albany, in the County of Albany, and State of New York, have invented or produced a new and original ornamental design for the plates of a Premium Cooking Stove, and I do hereby declare that the following is a full and exact description of the same, reference being had to the accompanying drawings and to the letters of reference on each of them.

Fig. 1. represents the side plate of said Premium Cooking Stove, with the doors attached. The ornaments marked A, and filling the panel of the said doors of the said stove side plate, together with the molding B, forming the panel of the door are claimed as original also the corner of said side, marked C.

Fig. 2. represents the front plate of the said Premium Cooking Stove with the doors attached, the ornaments filling the panels of the said doors being of the same style as those of the side plate of said stove, marked A, also moldings the same shape in combination with those of the side plate claimed as original, as also the corners marked D. Fig. 2.

What I claim as my invention and desire to secure by letters patent is the ornamental configuration of the plates of a Premium Cooking Stove, as fully set forth and described.

Witnesses.
